DESIGN FOR A COMBINATION CIGARETTE DISPENSER AND LIGHTER

Edward S. Lynch, New York, N. Y.

Application March 13, 1940, Serial No. 90,883

Term of patent 7 years

To all whom it may concern:

Be it known that I, Edward S. Lynch, a citizen of the United States of America and a resident of the Borough of Manhattan, city, county, and State of New York, have invented a new, original, and ornamental Design for a Combination Cigarette Dispenser and Lighter, of which the following is a specification, reference being

had to the accompanying drawing, forming a part thereof, in which the figure is a perspective view of a combination cigarette dispenser and lighter showing my new design.

I claim:

The ornamental design for a combination cigarette dispenser and lighter, as shown.

EDWARD S. LYNCH.
